UNITED STATES PATENT OFFICE.

ALBERT L. MOORHEAD, OF TELLURIDE, COLORADO.

METALLIC RAILWAY-TIE.

No. 871,065.

Specification of Letters Patent.

Patented Nov. 12, 1907.

Application filed March 22, 1907. Serial No. 363,846.

To all whom it may concern:

Be it known that I, ALBERT L. MOORHEAD, a citizen of the United States, residing at Telluride, in the county of San Miguel and State of Colorado, have invented certain new and useful Improvements in Metallic Railway-Ties, of which the following is a specification, reference being had therein to the accompanying drawing.

My invention relates to improvements in metallic cross ties and rail fastenings therefor, and more particularly to those set forth in an application filed by me on December 22, 1906 and bearing Serial Number 349,030.

The objects of the present invention are to provide the tie with means whereby it will be effectively prevented from slipping or creeping, and at the same time rendered stronger, and to provide the wedge or locking blocks with means for preventing them from working loose under the jar and vibration of trains passing over the track rails.

The above and other objects are accomplished by the improved construction illustrated in the accompanying drawings in which

Figure 1 is a side elevation of my improved cross tie showing track rails secured thereon; Fig. 2 is a top plan view of the same; Figs. 3 and 4 are detail sectional views taken respectively on the planes indicated by the lines 3—3 and 4—4 in Fig. 2; and Fig. 5 is a detail horizontal section taken on the plane indicated by the line 5—5 in Fig. 4.

My improved metallic tie 1 is cast in a single piece and has at its ends two substantially rectangular blocks 2 which are united by a reduced central portion 3. The blocks 2 have flat upper surfaces 4 which terminate at their outer ends in downwardly inclined surfaces 5 formed by beveling the outer ends of the tie, and at their inner ends by a depression or cavity 6 formed in the top of the central portion of the tie to provide the reduced connecting portion 3. This central connecting portion 3 is further reduced by having its opposite side faces 7 recessed or of substantially concave form, as clearly shown in Fig. 2. The bottom of the portion 3 lies in the plane of the bottom of the ends or blocks 2 of the tie, and upon said bottom faces 35 of these blocks are formed integral, longitudinally extending, depending ribs 8 for the purpose of preventing the tie from creeping with the rails or shifting either longitudinally or transversely of the track. The ribs or projections 8 are preferably straight and extend the full length of the blocks, two or more being provided upon each one, as clearly shown in Fig. 3. These ribs have their opposite vertical faces beveled downwardly and inwardly so that said ribs are tapered in cross section to permit them to be readily driven into the roadbed and to cause them to more effectively prevent the shifting of the tie.

In the tops of the blocks 2 are formed transversely extending rail seats 9 which are of slightly less depth than the height of the track rails 10. The latter have their base flanges resting upon the bottom of said seats and the outer walls 11 of said seats are shaped to snugly fit the outer faces of the base flanges, webs and heads of the rails, as clearly shown in Figs. 1 and 4. Upon the walls 11 are formed inwardly projecting integral studs or lugs 12 adapted to enter transverse openings 13 formed in the webs of the meeting ends of the rails, as clearly shown in Figs. 4 and 5. The inner walls 14 of the seats 9 are inclined with respect to the longitudinal axis of the body of the tie and in them are formed, preferably two, transversely extending grooves 15, the inner walls 70 of which have the same inclinations as the walls 14. The track rails are retained in the seats by wedge blocks 16, the outer faces 17 of which are shaped to fit the inner faces of the base flanges, webs and heads of the track rails and the bottoms of which rest upon the bottoms of 75 the seats 9, as clearly shown in Fig. 4. The inner walls 18 of the blocks 16 have the same bevel or inclination as the walls 14 of the seats 9 which walls they are adapted to engage, and upon them are formed longitudinally extending and laterally projecting ribs or tongues 20 80 which are adapted to enter the grooves 15 and which have their outer walls beveled, as clearly shown in Fig. 5. The blocks 16 are driven transversely or laterally into the seats 9 between the track rails and the inner walls 14 and they are adapted to be locked in position 85 after being driven in to the desired extent, by bolts, pins, or the like 21, passed vertically through alining apertures 22 which are arranged in longitudinal series in the tongues or ribs 20. As shown, the locking elements 21 are in the form of bolts which have their flat heads 23 90 engaged with the side faces of the blocks 2 and their lower ends, which project beyond the lowermost tongue or rib 20, apertured to receive split pins or the like 24, which will prevent them from being casually displaced from the apertures 22. It will be observed that these 95 locking pins will effectively retain the wedge blocks in their seats and at the same time permit of their ready removal for the purpose of repairing or replacing the track rails. It will be further observed that the provision of a plurality of the apertures 22 permits the 100 wedge blocks to be locked at any point so that the track rails will be held rigidly in the tie. In the tops of the blocks 16 are formed longitudinally extending grooves 25 which are arranged close to and beneath the inner sides of the heads of the track rails and are adapted to 105 receive the flanges upon the wheels of cars or the like passing over the rails.

From the foregoing it will be observed that a tie constructed as above described will be exceedingly strong and durable and will provide a substantial support for 110 the track rails. The provision of the blocks 2 and the seating of the rails in them so that the rails are almost

entirely surrounded by the tie and the locking blocks, causes the rails to be effectively retained and rigidly held. The provision of the depending ribs 8 upon the bottoms of the blocks 2 effectively prevents the tie from slipping or creeping either longitudinally with the rails or transversely of the track. The locking pins 21 permit the wedge blocks to be securely retained at any desired adjustment so that said blocks may be tightened from time to time to cause the rails to be rigidly held 10 and so that the blocks may be properly adjusted upon new rails that are replaced for old, worn out ones.

Having thus described my invention what I claim and desire to secure by Letters Patent is:

1. A metallic railway tie comprising a cast metal body having large end blocks united by a reduced connecting portion, said end blocks having seats in their upper faces for the reception of track rails and upon their lower or bottom faces longitudinally extending depending ribs to prevent them from slipping or creeping.
2. A metallic railway tie comprising a body cast in one piece and having large end blocks of substantially rectangular form united by an integral reduced connecting portion having a recessed top and recessed vertical sides, said end blocks having flat vertical side faces and flat horizontally disposed top faces with downwardly and outwardly beveled outer ends, said end blocks being also formed in their flat top faces with transversely extending rail seats, said end blocks having flat bottom faces disposed in the plane of the bottom face of the reduced connecting portion of the tie and longitudinally extending downwardly tapered ribs formed integral with said end blocks upon their flat bottom faces, substantially as set forth.
3. The combination of a metallic railway tie having adjacent to its ends transverse rail seats of slightly less depth than the height of the track rails, the outer walls of said seats being shaped to fit the outer faces of the heads, webs and base flanges of the rails, the inner walls of said seats being inclined transversely of the tie and having grooves, the inner walls of which are also inclined, track rails arranged in said seats and engaged with their outer walls, wedge blocks in said seats and having their outer faces shaped to fit the bottom of the head and the inner faces of the webs and base flanges of the rails, the inner faces of said blocks being inclined and formed with longitudinally extending tongues to enter said grooves in the inner walls of said seats, said tongues

being formed at the small end of the blocks with a longitudinal series of vertically alining apertures and said blocks being formed in their top faces with longitudinally 50 extending grooves or channels to receive the flanges of car wheels and locking pins passed vertically through said apertures in the tongues and formed with heads to engage the side faces of the tie, substantially as shown and described.

4. The combination with a metallic railway tie having end blocks united by a reduced central portion, said end blocks having longitudinally extending depending ribs upon their bottom faces and transversely extending rail seats in their top faces, said rail seats being of slightly 60 less depth than the height of the track rails and having their outer walls shaped to engage the outer faces of the track rails, the inner faces of said walls being inclined and formed with transverse grooves, track rails arranged in said seats and engaged with their outer walls, wedge 65 blocks arranged in said seats and having their outer faces shaped to engage the inner faces of the track rails, said blocks having grooves in their tops to receive the flanges of car wheels, said blocks also having their inner faces inclined and formed with longitudinally extending tongues 70 to enter the grooves in the inner walls of said seats, said tongues being formed with a longitudinal series of apertures adjacent to the small ends of said wedge blocks, and locking pins passed through said apertures and engaged with one of the side faces of the tie, substantially 75 as shown and described.

5. The combination of a metallic railway tie having upon its top adjacent to its ends transverse rail seats formed with outer walls to engage the outer faces of track rails and with inner walls inclined transversely of the tie 80 and provided with grooves, track rails in said seats and having their outer faces engaged with the outer walls of said seats, metallic wedge blocks driven into said seats and having outer faces to engage the inner faces of the track rails, the inner faces of said blocks being formed 85 with tongues to enter said grooves, said tongues having at their small ends a longitudinal series of vertical apertures and locking pins passed through said apertures in the tongues and engaged with the side faces of the tie to adjustably retain said blocks in said seats, substantially 90 as shown and described.

In testimony whereof I hereunto affix my signature in presence of two witnesses.

ALBERT L. MOORHEAD.
